DOUBLE SEAL MILK CAN

John A. Hopwood, Westfield, N. J.

Application November 14, 1945, Serial No. 628,596

5 Claims. (Cl. 220—42)

1

This invention relates to milk cans and more particularly to milk delivery cans, the invention being especially directed to the cover of the can.

Heretofore milk delivery cans have generally been provided with so-called "umbrella" covers which comprise a central section having a rim adapted to extend into the neck of the can and the upper portion of which center section is laterally extended to form an umbrella flange which overlies the outer edge of the lip or bowl of the can, so that rain water or other water spilled on top of the can or resulting from melting of ice will flow off the periphery of the umbrella without entering into the bowl of the neck. Umbrellas of prior cans, however, have been so made as to be spaced some little distance from the outer edge of the bowl, which, in practice, is generally rolled or curled back upon itself to give a reinforced edge.

According to the present invention, the center section of the cover embodies a rim to fit into the neck of the can as before. The umbrella is formed of a separate piece secured to the periphery of the center section and extends outwardly in a radial direction and is provided at its outer edge with a depending skirt, preferably of somewhat heavier material and so positioned with respect to the rim of the cover that, when the rim is fitted into the neck of a can, the said skirt will contact with the outer periphery of the lip or bowl of such can to thereby provide a double seal. With this double seal water or other impurities cannot pass under the umbrella into the lip or bowl of the can and there is thus provided a much more sanitary closure for the contents of the can than the old fashioned umbrella type of cover could produce. At the same time I provide a stronger cover and one which will better withstand the rough usage to which milk can covers are commonly subjected.

In the preferred embodiment of the invention, the umbrella section is in the form of an annulus provided at both its inner and outer peripheries with flanges. The flange at the inner periphery is welded to the center section of the cover in a face abutting joint while the flange at the outer periphery of the umbrella is half lapped into the skirt to provide a flush joint, and welded in place so as to eliminate crevices in which dirt or other foreign matter might lodge. The lower or free edge of the skirt is preferably flared outwardly to give it a lead when placing the cover on the can and is rounded over to produce a smooth edge.

A cover of the character described may be used with a conventional milk can provided with a curled or rolled edge on its lip, but I prefer to use this cover in connection with a novel form of lip. This novel form of lip is produced by providing it, at its outer periphery, with a down turned

2

flange of cylindrical form and this down turned flange is half lapped into a substantially cylindrical ring of thicker section and firmly welded into place so that the outer surface of this ring is substantially cylindrical in form to better coat with the inner surface of the skirt of the cover and thus form therewith a surface seal.

Features of the invention, other than those adverted to, will be apparent from the hereinafter detailed description and appended claims, when read in conjunction with the accompanying drawing.

The accompanying drawing illustrates one practical embodiment of the invention, but the construction therein shown is to be understood as illustrative, only, and not as defining the limits of the invention.

Figure 1 is a central section of a can and cover embodying the present invention, that portion of the can below the breast being broken away.

Figure 2 is a like view showing the cover of this invention associated with a conventional can.

In the drawings, 1 designates the neck of the can which is superimposed upon a conventional breast 2 and is provided at its top with a lip or bowl 3. In the form of the invention shown in Figure 1, the bowl is frustoconical and it is provided at its outer edge with a down turned relatively shallow flange 4. Embracing this shallow flange is a ring 5 of much heavier metal and the inner surface of this ring 5 is rabbeted at its upper edge, as indicated at 6, to receive the flange 4 which is welded to the ring 5 by welding metal 7 to form a flush joint devoid of cracks or crevices. The outer surface of the ring 5 is substantially cylindrical.

The cover embodies a center section 8 provided with a depending rim 9 adapted to have a sliding fit with the interior of the neck 1 and, arranged peripherally of the center section and forming in effect a continuation of its top, is an umbrella 10 having at its inner edge a downwardly extending flange 11 and at its outer edge a similar flange 12. The flange 11 is welded to the outer surface 15 of the rim by welding metal 13 which forms a closed joint without cracks or crevices. The flange 12 at the outer edge of the umbrella is fitted into a rabbet 14, formed in the outer upper portion of a skirt 15 which is of somewhat greater thickness than the thickness of the stock of the remainder of the cover or of the can. In practice, I preferably use stock of the same thickness for the ring 5 and the skirt 15, although the ring 5 may be somewhat heavier if desired. The ring 5 is welded to the umbrella by welding metal indicated at 16, to form a closed joint without cracks or crevices.

The parts are so proportioned that, when the rim is thrust down into the neck 1, the skirt 15 will have a sliding fit with the ring 5 and the lower

edge of the skirt 15 is flared outwardly as shown at 17, so that these parts may smoothly come into engagement with one another.

When a cover is in place the ring will fit firmly into the neck while the skirt 15 will closely embrace the ring 5, so as to form, in conjunction with the ring, a second seal. In practice the neck, as well as the rim, may have a slight downward taper and the ring 5 and skirt 15 may be provided with a corresponding upward taper, so that the double seal is formed with a tapered fit, adapted to compensate for slight variations in can and cover diameters. The stock of the can and cover, with the exception of the ring 5 and skirt 15, are of sheet metal and there is sufficient yield therein to compensate for slight irregularities, slight difference in size and wear.

Figure 1 shows the preferred form of the invention, wherein the can and cover are arranged for the best coaction. It is possible, however, to use a cover of the kind shown in Figure 1 on a conventional form of can, such as shown in Figure 2, wherein the outer edge of the lip or bowl 3a is curled as shown at 18. The skirt 15 may coact tangentially of this curled edge, as shown in Figure 2, to give a line contact which will suffice to produce the second seal, but is not as efficient as the structure of Figure 1.

The foregoing detailed description sets forth the invention in its preferred practical form, but the invention is to be understood as fully commensurate with the appended claims.

Having thus fully described the invention, what I claim as new and desire to secure by Letters Patent is:

1. A milk can comprising a neck with a superimposed bowl provided at its outer edge with a downwardly extending flange, a ring embracing said flange and provided with a rabbet in which the flange is received, said flange being welded in said rabbet, in combination with a cover having a center section with a rim adapted to fit into the neck of the can and provided peripherally with a radially extending umbrella the inner edge of which is welded to the center section and the outer edge of which is provided with a downwardly extending flange, and a skirt rabbeted at its upper end to receive said flange which is welded in place therein, said skirt having an internal diameter adapted to engage with the external surface of the ring on the bowl when the rim of the cover is introduced into the neck of the can.

2. A milk can comprising a neck with a superimposed bowl provided at its outer edge with a downwardly extending flange, a ring embracing said flange and provided with a rabbet in which the flange is received, said flange being welded in said rabbet, in combination with a cover having a center section with a rim adapted to fit into the neck of the can and provided peripherally with a radially extending umbrella the inner edge of which is welded to the center section and the outer edge of which is provided with a downwardly extending flange, and a skirt rabbeted at its upper end to receive said flange which is welded in place therein, said skirt having an internal diameter adapted to engage with the external surface of the ring on the bowl when the rim of the cover is introduced into the neck of the can, said ring being of greater thickness than the thickness of the stock from which the bowl is formed.

3. A milk can comprising a neck with a superimposed bowl provided at its outer edge with a downwardly extending flange, a ring embracing said flange and provided with a rabbet in which the flange is received, said flange being welded in said rabbet, in combination with a cover having a center section with a rim adapted to fit into the neck of the can and provided peripherally with a radially extending umbrella the inner edge of which is welded to the center section and the outer edge of which is provided with a downwardly extending flange, and a skirt rabbeted at its upper end to receive said flange which is welded in place therein, said skirt having an internal diameter adapted to engage with the external surface of the ring on the bowl when the rim of the cover is introduced into the neck of the can, said ring being of greater thickness than the thickness of the stock from which the bowl is formed, and said skirt being of greater thickness than the thickness of the stock from which the umbrella is formed.

4. A milk can comprising a neck with a superimposed bowl provided at its outer edge with a downwardly extending flange, a ring embracing said flange and provided with a rabbet in which the flange is received, said flange being welded in said rabbet, in combination with a cover having a center section with a rim adapted to fit into the neck of the can and provided peripherally with a radially extending umbrella the inner edge of which is provided with a downwardly extending flange, and a skirt rabbeted at its upper end to receive said flange which is welded in place therein, said skirt having an internal diameter adapted to engage with the external surface of the ring on the bowl when the rim of the cover is introduced into the neck of the can.

5. A milk can comprising a neck with a superimposed bowl having an outer edge which is thickened and reinforced, in combination with a cover having a center section with a rim adapted to fit into the neck of the can and provided peripherally with a radially extending umbrella, the outer edge of which is provided with a downwardly extending flange, and a skirt rabbeted at its upper end to receive said flange which is welded in place therein, said skirt having an internal diameter adapted to engage with the external surface of the thickened reinforced outer edge of the bowl when the rim of the cover is introduced into the can.
